UNITED STATES PATENT OFFICE

ALBIN VITALIS CARLSON, OF SCHWARTAU, NEAR LUBECK, GERMANY

METHOD OF INCREASING THE OUTPUT OF MECHANICAL ROASTING FURNACES AND
THE LIKE

Application filed April 9, 1928, Serial No. 268,575, and in Sweden April 25, 1927.

In ordinary roasting furnaces known before with several hearths in different levels the charge is heated by means of a flame on the top hearth, and then by means of a stirring device or another device transporting and mixing the heated mass is conducted to the following hearths, where the reactions—for instance roasting or chlorination roasting—begin and continue. The heat exchange 5 on the top hearth is here very imperfect as the great layer thickness necessary for a high output and the little heat-conducting power of the charge are hindering so that a long influence of the heating flame is required. 10 Further the intimate contact necessary for a quick and perfect heat exchange between the heating flame with its hot combustion gases and the charge is wanting. The combustion gases leave the top hearth with a temperature 15 of many hundred degrees without having ignited the charge or in sufficient degree transmitted heat to the charge or to furnace-walls or hearths. The insufficient heating of the charge reached on the first hearth is increased on the following hearths by means of 20 the hot roasting gases. For the most the reaction temperature for the intended process is reached first on the third or fourth hearth. The transport of the charge in the different 25 hearths generally takes place alternately from centrum to periphery and from periphery to centrum by means of a central shaft, the motion velocity of which is dependent on and adjusted according to the reaction 30 velocity of the charge in its turn dependent on the quickness with which the charge can be heated and ignited. Against an increased output through the increased motion velocity of the central shaft there stand an unfavourable 35 roasting-effect and a bad heat exchange. 40

This invention effects that the output of the furnace is essentially increased—more than 40% higher output has been obtained at durable output on working scale—that 45 through the suitable arrangement of the heating flame a more perfect heat exchange is reached and fuel up to 40% spared and that the working of the furnace becomes simpler and the roasting essentially better. These 50 advantages are reached thereby that the heat-

ing flame is at the combustion pressed on to the charge and ignites the sulphur therein, and that the hot exhaust gases from the top hearth are not, as before, conducted directly to an outlet but are blown into the grooves 55 formed in the charge at the transport and then forced to pass chambers or channels through which the charge is conducted to the furnace.

Through a suitable arrangement of burners 60 or a system of burners the exhaust gases for reaching a rational heat exchange and ignition of the sulphur are caused to pass over the charge and after circulatory movement be sucked into the drying and heating apparatus. At the combustion the fuel current—oil, gas and coal dust—is conducted tangentially into the furnace by an annularly surrounding air-current, and passes over the transport grooves and shoulders situated next 65 to the furnace wall. The current is directed obliquely downwards and along the charge so that a combustion flame is formed passing over the transport grooves and shoulders. By introducing the fuel current in this manner in one place or with in rotary respect the same direction in several places in the furnace the flame and the exhaust gases obtain a circulatory movement gradually moving 70 against the outlet situated in the middle 75 of the furnace-arch. By this there will be on the top hearth high temperature differences between the combustion gases and the charge, and owing to that a very complete heat exchange will take place. Simultaneously, by the intimate contact of the heating 80 flame with the dried and pre-heated charge the combustible sulphur therein is ignited and through the continuous stirring of the charge at the transport the combustion of 85 the sulphur spreads quickly all through the charge. On the top hearth it is to ignite the combustible sulphur in the charge quickly. In order to realize that what is intended, it is necessary that the charge is dry and 90 heated and that it is passed over by the combustion flame and the exhaust gases. To maintain the charge at the reaction temperature or give it temperatures above the reaction 95 temperature or to increase the reaction 100

velocity burners may be disposed even on the other furnace hearths. Preheated air, if desired also steam in small quantities, may suitably be blown in either at the combustion or for hastening the reaction.

5 In the means for drying and pre-heating, which may be disposed within or outside the furnace, an intimate contact takes place between the charge flowing down and the hot exhaust gas current arising so that a rather perfect utilization of heat of the exhaust gases is reached and the charge flows down on the top hearth with a temperature making possible that the roasting reaction begins all ready on this hearth or at the transport of the charge down to the next hearth. One can then give the central shaft with the transport means increased velocity by which a brisker transport and greater output are obtained. It is self-evident that the increased output and the better utilization of the heating flame entail very considerable technical and economical advantages.

25 The bringing of the exhaust gases into intimate contact with the charge while passing through the same may be performed in different manners according to the sort and the physical properties of the charge. In an extension on or in the furnace one can let 30 the charge fall down in steps while the exhaust gases passing through and against the same. One can also lead the exhaust gases through a rotating drum, through which the charge is conducted in such a manner that it 35 falls from the top downward in the drum at the rotation, or lead the charge forward through screws, stirring devices or the like in a closed chamber, through which the exhaust gases from the furnace are led.

40 Figure 1 is a side elevation, partly in vertical section of the upper portion of a roasting furnace.

Fig. 2 is a sectional view on line 2-2 of Fig. 1.

45 Fig. 3 is a vertical section through the upper part of the furnace.

Fig. 4 is a sectional view on line 4-4 of Fig. 3.

50 Fig. 5 is a vertical sectional view of a modified form of the invention, the rotary drum being shown in elevation.

Fig. 6 is a sectional view on line 6-6 of Fig. 5.

55 Fig. 7 is a vertical sectional view of another modified form of the invention, and,

Fig. 8 is a sectional view on line 8-8 of Fig. 7.

60 In these figures *a* indicates the burners pointed obliquely downwards. In the pre-heating chamber above the real furnace plates *c* are disposed on the rotary shaft *b*, and on these plates the charge is fed under influence of skimmers *d*. In the modification according to Figures 5 and 6 the material is conducted in counter-current against the exhaust

gases through a rotating drum *e*. Figures 7 and 8 show a closed feeding chamber *f*, through which the material is conducted by means of a rotating transport device under pre-heating through influence of the exhaust gases.

Having now described my invention, what I claim as new and desire to secure by Letters Patent is:

A method of operating mechanical roasting furnaces, wherein a combustion of supplied fuel and the contents of the material takes place during formation of flue gases which are led away, and wherein the charge of material into the furnace is carried in a direction in opposition to the flow of the gases of combustion and the material is repeatedly caused to fall freely in the current of passing gases to subject the material to intimate and prolonged action of the gases to preheat the material before it is subjected to reaction temperature, the fuel being admitted to the furnace in a tangential current pointed obliquely downwardly and passing directly over the material introduced into the furnace.

In witness whereof, I have hereunto signed my name.

ALBIN VITALIS CARLSON.
